UNITED STATES PATENT OFFICE.

THORNTON C. FRY, OF WYOMING, NEW JERSEY, ASSIGNOR TO WESTERN ELECTRIC COMPANY, INCORPORATED, OF NEW YORK, N. Y., A CORPORATION OF NEW YORK.

FILTERING CIRCUIT.

Application filed September 27, 1919. Serial No. 326,987.

To all whom it may concern:

Be it known that I, THORNTON C. FRY, a citizen of the United States, residing at Wyoming, in the county of Essex, State of New Jersey, have invented certain new and useful Improvements in Filtering Circuits, of which the following is a full, clear, concise, and exact description.

The present invention relates to the selective transmission of ranges or bands of frequencies and has for an object the attainment of more sharply defined boundaries for the selected bands or ranges of frequencies than have heretofore been found possible.

15 The importance of definitely limited bands in all systems in which the bands have an individual significance will be recognized. For example, in multiplex signaling systems in which the individual communication channels are distinguished from one another by the frequencies which the several channels employ, the more definite are the boundaries of the frequency range or band of each channel, the closer together in terms of frequencies can the channels be situated without their interfering with one another, and the greater is the number of channels therefore that can be included within a given available frequency range.

20 A feature of the invention is the use of low-pass and high-pass filters in combinations to give sharply defined boundaries to the transmitted bands or ranges of frequencies.

25 By low-pass filter is meant a filter which will transmit with negligibly small attenuation, currents of all frequencies between zero and a predetermined limit, while attenuating and substantially extinguishing currents of all frequencies above that limit, conversely, a high-pass filter is one that will attenuate and substantially extinguish currents of all frequencies between zero and a predetermined limit, but will transmit with negligibly small attenuation currents of all frequencies above said predetermined limit.

30 The filters that are preferably employed according to the present invention are suppression filters because this type of filter has the property of giving a sharp cutoff between the transmitted and the suppressed frequencies. In the patent to G. A. Campbell, No. 1,227,113 are given examples of a number of band filters which may be regarded as transmission filters, their object being

35 to transmit with negligible attenuation only a predetermined band or bands of frequencies. Each section of a band filter contains a series impedance element of one character and a shunt impedance element of a different character. According to the frequency characteristics for which the band filter is 40 designed, the shunt impedance may consist of a single impedance element or a parallel inductance-capacity impedance, while the series impedance may consist of a single impedance element or a series inductance-capacity impedance. The function of the suppression filter is the converse of that stated of the band filter, the object being to transmit freely all 45 frequencies except a predetermined range. In general, and as employed throughout the specification and claims, the term "suppression filter" is used to designate a filter which 50 consists of a plurality of sections connected in seriatim, each having series impedance and shunt impedance, and in which either or both of the following conditions are met: (1) The series impedance of a section is 55 equivalent at all frequencies to that of a capacity element and an inductance element in parallel; (2) the shunt impedance of a section is equivalent at all frequencies to that of a capacity element and an inductance element in series. A low-pass or a high-pass 60 filter, as defined above, may be constructed on the principle of the transmission band filter or the suppression filter. The advantage of the suppression type of filter for the 65 purposes of the present invention as above 70 stated, is that the boundary between the ranges of transmitted frequencies and suppressed frequencies may be made very sharp. The suppression type of filter is more fully 75 described in the patent to G. A. Campbell, 80 No. 1,498,600 dated May 13, 1924.

85 In the drawings, Figs. 1 and 2 illustrate two ways of combining suppression filters. Figs. 3 and 4 each show a manner of combining successive pairs of suppression filters 90 and Fig. 5 illustrates diagrammatically an application of the principle of the invention to a carrier signaling system.

95 Figs. 1 and 2 are largely self-explanatory. In Fig. 1, the low-pass suppression filter LP has the property of transmitting only applied frequencies which lie between zero and the limit N while the high-pass suppression filter HP suppresses all frequencies except those between a predetermined 100

cutoff frequency M and infinity. These properties are indicated on the drawing by a minus (−) sign following N and a plus (+) sign following M . If $N > M$ there will 5 be a band of width $N - M$ which is transmitted by both filters, and this band will have a sharply defined upper boundary due to the cutoff of the filter LP and a sharply defined lower boundary due to the cutoff 10 of the filter HP . The order of the filters in the circuit can be the reverse of that shown just as well, and either arrangement will give the band $N - M$.

In Fig. 2, the suppression ranges of the 15 filters LP and HP preferably overlap, that is, the transmission ranges do not meet, leaving a gap of suppressed frequencies in their common output circuit. If, as before, $N > M$ the frequencies that are suppressed 20 lie in the sharply defined band $N - M$. The same type of filter might be used in both Figs. 1 and 2. As in the case of Fig. 1, it is immaterial to which terminals of the circuit the currents are applied. Since the 25 combination in Fig. 2 will pass all frequencies below M and above N , if $M > N$ it passes all frequencies while, as stated, if $N > M$ it suppresses the band M to N .

In Fig. 3, if a wide range of frequencies 30 is introduced at the terminals 1, 2 all will be transmitted to the points 3, 4 except the sharply defined band $Q - P$ and a circuit may be tapped off at the points 3, 4 as indicated for conveying the frequencies lower 35 than P and greater than Q for any desired purpose. Of the frequencies present at points 3, 4, all will be transmitted to the points 5, 6 except those lying within the band M to N . If $M > Q$ or if $N < P$, 40 there will be two suppression bands at points 5, 6 with a sharply defined transmitted band between the suppressed ranges. If M and N lie between P and Q , the second pair of filters, as indicated in Fig. 3 45 would of course have no useful function, which means that when this condition holds, the pair of filters which has the narrowest suppression band should come first in the circuit.

In Fig. 4, an arrangement of filters is indicated for giving a different sharply defined band of transmitted frequencies in each of the circuits, 7, 8 and 9, 10 and 11, 55 12. The high-pass filters HP_1 , HP_2 , and HP_3 are placed in series in the line and they should be so arranged that $P > N > M$. All frequencies higher than M will be transmitted by the filter HP_1 and all lower frequencies will be suppressed. If the low- 60 pass filter LP_1 transmits only the frequencies from zero to the predetermined limit N' , which is assumed to be greater than M , the band $N' - M$ will be transmitted to the branch circuit 7, 8. In the case of a wave 65 signaling system the frequencies transmitted

by the branch 7, 8 will preferably be outside the range of those in branch 9, 10 in order to avoid cross-talk. N' is preferably slightly less than N in this case, although the degree to which the value of N' can be 70 made to approach that of N in practice will depend upon the requirements and upon the sharpness of the cutoffs of the filters, for this property can be varied at will, and upon the number of sections in a filter. The 75 range of frequencies transmitted by HP_2 will therefore be from a frequency slightly above the upper cutoff value of LP_1 upwards and if $P' > N$, there will be a sharply defined band of width $P' - N$ transmitted 80 through filter LP_2 to the branch 9, 10. By extension of the principle, any desired number of bands of frequencies of the same or of different widths may be selectively transmitted to a succession of branch circuits, such as those indicated. As in the case of the preceding Figures the direction of application of the currents may be the opposite of that described, and branches 7-8, 9-10, and 11-12 instead of serving as receiving circuits may be transmitting circuits. If currents of different frequencies are applied to branches 7-8, 9-10, etc., discrete bands of frequencies of widths 85 respectively determined by the combinations 90 of filters used, will appear in the circuit 1-2 which is now the output circuit. Instead of using high-pass filters in series and a low-pass filter in each branch, the reverse arrangement can be used as shown in connection with the next figure.

In Fig. 5, the line 15 may be a composite carrier current telephone line or other signaling line employing a number of frequencies both greater and less than the upper limit of the speech frequency range. If S_1 represents the upper limit of essential voice frequencies, the filter LP_1 , which passes only the frequencies from zero to S_1 , will permit the speech waves to pass to the line 16, but will keep all higher frequencies from 105 passing. The high-pass filter HP_1 , will serve to block the passage of all frequencies in the essential voice range to the circuits 17, but will freely transmit all the frequencies 110 lying above a predetermined limit S_2 , which may be made very close to the limit S_1 by virtue of the definite cutoff property of the filters LP_1 and HP_1 . These frequencies 115 above S_2 may comprise a number of carrier waves each modulated by speech or some other wave of comparatively low frequency, and as is well known, in case the carrier waves are speech-modulated, there will be 120 present a number of bands or ranges of frequencies, each range comprising frequencies extending from or near the respective carrier frequency in either or both directions for a limited distance. All of these 125 bands of frequencies are transmitted through 130

the coil 18 and they are to be separately transmitted to the respective branch circuits 19, 20, 21 and 22. For this purpose, a number of low-pass filters LP_2 to LP_5 are placed in series and each branch 19, 20, etc., contains a high-pass filter HP_2 , HP_3 , etc. It will be noted that this arrangement is the converse of that shown in Fig. 4, but either arrangement is suitable. The upper limit of the frequency range transmitted by each of the filters LP_2 , LP_3 and LP_4 is greater than that of LP_5 so that none of the three filters will obstruct the passage of currents from the coil 18 to the filter LP_5 of any frequency which the filter LP_5 is capable of transmitting. Of those frequencies from S_2 upwards which are thus transmitted to the filter LP_5 , this filter transmits only the frequencies below the predetermined upper limit $S_2 + C$ and only the band of width C , lying between S_2 and $S_2 + C$, will therefore be transmitted to the branch circuit 22. It is assumed for convenience that all the bands that are to be separated are of equal width, although this is not at all necessary. Of the frequencies from S_2 upwards that reach the filter LP_2 , only those within the upper predetermined limit $S_2 + 2^c + D$ will be transmitted giving a transmitted range of frequencies between S_2 and $S_2 + 2^c + D$. Of this range only the frequencies above the limit $S_2 + C + D$ will be transmitted by the filter HP_4 and therefore the range of frequencies transmitted to the branch 21 will consist only of frequencies between $S_2 + C + D$ and $S_2 + 2^c + D$ or a band of width C . D represents the frequency interval between the successive bands and is assumed to be the same throughout the bands present although this is, of course, not a necessary condition. The more sharply defined are the cutoff properties of the filters, the smaller can D be made without having interference between the adjacent bands. By extension of the same principle, it is seen that each band C is separately delivered to its circuit 20, 19, etc., in which there may be suitable receiving apparatus, not shown.

The circuit 23 may lead to transmitting apparatus employing frequencies higher than S_2 to be impressed upon the line 15. The usual balancing-net 24 for the line circuit 15 is shown and the coil 18 is indicated as being the usual conjugate coil for eliminating interference between incoming and outgoing transmissions.

The circuits 19, 20, 21, 22 instead of being receiving circuits as described might contain sources of currents of different frequencies higher than S_2 to be impressed on line 15. Or the transmitting circuit to which conductors 23 lead may contain filters similar to LP_2 , HP_2 , LP_3 , HP_3 , etc., or any other desired selective means.

It will be seen that a great many other combinations of high-pass and low-pass filters to secure desired transmitted or suppressed bands are possible in accordance with the principles that have been herein set forth, and it is to be understood that the various circuit arrangements shown are for illustrative purposes only and they do not restrict the invention, which is to be limited only by the scope of the appended claims.

What is claimed is:

1. Means for transmitting a band of frequencies comprising a low-pass suppression filter and a high-pass suppression filter in series, the frequencies of said band being common to the transmission ranges of both of said filters.

2. A selective circuit including high-pass suppression filters and low-pass suppression filters, the filters of one kind being connected in series, each filter of the other kind being connected to the output terminals of a different filter of said one kind, the transmission frequency range of each filter of said other kind overlapping that of the filter to which it is connected.

3. A selective circuit including high-pass suppression filters and low-pass suppression filters, the filters of one kind being connected in series, each filter of the other kind being connected to the output terminals of a different filter of said one kind, the transmission range of each filter of said other kind overlapping that of the filter to which it is connected, and the transmission range of each of said filters in series being exclusive of a portion of the transmission range of each of the filters which precede it in the series.

4. A selective circuit including a high-pass filter comprising a line including a plurality of sections, each section comprising an impedance in series with the line and an impedance in shunt of the line, one of said impedances being composed of inductance and capacity so related as to oppose the transmission through the filter of current of the frequency for which the reactance of said inductance equals the reactance of said capacity, the other impedance opposing the transmission through said filter of all currents of frequencies less than said frequency, and a low-pass filter connected in series with said high-pass filter and having its transmission range overlapping that of said high-pass filter.

5. The circuit arrangement of claim 4, said low-pass filter comprising a line including a plurality of sections, each of which includes impedance in series with the line, an impedance in shunt of the line, one of said impedances comprising inductance and capacity so related as to oppose the transmission through said filter of current of the frequency for which the reactance of said

inductance equals the reactance of said capacity, the other impedance opposing the transmission through said filter of all currents of frequencies higher than said frequency.

6. A selective system comprising a plurality of high-pass filters and low-pass filters as claimed in claim 5 each filter of one kind being in series with a filter of the other kind, the filters of one kind being all connected in series and a branch circuit connected to the output of each filter of the other kind.

7. A selective system comprising a line having a plurality of low-pass suppression filters in series in said line, the cutoff frequencies of the respective filters being successively lower, a branch circuit connected to the output terminals of each of said filters, a high-pass filter in said branch circuit having a cutoff frequency at least as high as that of the low-pass filter next succeeding in the series the low-pass filter to which said branch circuit is connected.

8. A transmission line for conveying currents of different frequencies, a plurality of circuits associated with said line, each circuit conveying currents of a different range of said frequencies, selective means between said line and said circuits comprising low-pass filters associated with said line in series with one another, and high-pass filters in said respective circuits each connected to the output of one of said low-pass filters and having a transmission frequency range overlapping that of the low-pass filter to which it is connected.

9. A high frequency composite signaling line for transmitting currents of speech frequencies and currents of frequencies outside the range of speech frequencies, a low-pass suppression filter in series with said line for passing only currents including the highest essential speech frequency and lower frequencies, a high-pass suppression filter in parallel with said low-pass filter for transmitting currents of frequencies higher than the speech frequency range, a plurality of branch circuits, a selective system associated with said high-pass filter for conveying a different band of high frequency currents between said line and each of said branch circuits comprising low-pass suppression filters in series having successively lower cutoff frequencies, one of said branch circuits being connected to the output of each of said low-pass filters which are in series and high-pass suppression filters in the respective branch circuits, the cutoff frequency of each of which is at least as high as that of the next succeeding low-pass filter in the series.

10. Means for transmitting currents of a band of frequencies comprising a high pass filter and a low pass filter in series having overlapping frequency transmission ranges, at least one of said filters being a suppression filter whereby the transmitted band of frequencies is sharply defined at least at one boundary.

11. A plurality of pairs of suppression filters one filter of each pair transmitting only currents of frequencies higher than a certain definite cut-off value and the other transmitting currents of frequencies only below a certain definite cut-off value, a circuit common to all of said pairs of filters for conveying currents of frequencies transmitted by each of said filters, and a branch circuit individual to each of said pairs of filters for conveying currents of only the frequencies that are transmitted by the filters of said pair.

In witness whereof, I hereunto subscribe my name this 26th day of September A. D., 1919.

THORNTON C. FRY.
